DERRICK

Filed April 21, 1928

UNITED STATES PATENT OFFICE

EARL H. MORRIS, OF UNIONTOWN, KENTUCKY

DERRICK

Application filed April 21, 1928. Serial No. 271,898.

This invention relates to derricks and more particularly to an improvement of the mast mountings of stiff leg derricks.

An important object of the invention is to provide a novel and improved mounting for the derrick mast, enabling the same to be very readily shifted from its normal or vertical position to a horizontal position where it overlies the derrick body structure, so that the mounting may be conveniently employed with any stiff leg derricks or with folding derricks of the type shown in my co-pending application, Serial No. 223,353, filed October 1, 1927, for Derricks of which application the subject matter of this application is a continuation in part.

A further and more specific object of the invention is to provide a rotatable mast support upon which the mast is mounted for movement from vertical to horizontal positions and in which connections are provided whereby the mast, when in its vertical position, is very rigidly and firmly held to the rotatable mounting structure.

These and other objects I attain by the construction shown in the accompanying drawing, wherein for the purpose of illustration is shown a preferred embodiment of my invention and wherein:

Figure 1 is a side elevation partially in section showing a mast mounting constructed in accordance with my invention;

Figure 2 is a section on the line 2—2 of Figure 1;

Figure 3 is a section on the line 3—3 of Figure 1;

Figure 4 is a fragmentary plan view showing the derrick mast shifted to horizontal positions;

Figure 5 is a detail sectional view showing the manner of locking the bull wheel in position upon the base.

Referring now more particularly to the drawings, the numeral 10 generally designates the lay beams of the main carriage of a derrick and 15 a supporting bed applied to the carriage at one end thereof, providing the mounting for a bull wheel pivot pedestal, generally designated at 16. This bull wheel pivot pedestal comprises a casting having a cen-

tral bore 39. The lower surface of the casting has ears 40 mounting the pivot shaft 41 of sheaves 42 which are substantially tangential to the axis of the bore. Surrounding the bore at the upper surface of the casting is a boss 44 and surrounding this boss in spaced relation thereto is a flange 45. The boss and its associated flange provide a step bearing for the hub 46 of the bull wheel which has a depending flange 47 surrounding the boss and extending into the annular space provided between the boss and flange. The flange 47 and boss 44 have coacting means at 48 preventing vertical displacement of the bull wheel hub. The rim of the bull wheel, indicated at 49, has a grooved periphery and is supported from the hub by radiating spokes 50. Supported from the rim in spaced relation thereto by rigid braces 51 is a yoke, generally designated at 52, three sides of which are integrally connected and the fourth side of which is a removable plate 53.

The braces 51 are so arranged that they will not interfere with the passage of a mast 54 through this open side.

Upon the upper surface of the bull wheel hub are arranged spaced pairs of ears 55 and 56 having apertures which align for the reception of a pivot bolt 57 and an anchor pin 58. The derrick mast 54 has rigidly secured to the lower end thereof a casting 59 embodying apertured ears for the passage of the pivot pin 57 and anchor pin 58. This casting has also spaced apertured ears 60 at one side thereof through which is passed a pivot pin 61 providing a pivot for the lower end of the boom 37. The hub 46 of the bull wheel and casting 59 of the mast have aligned apertures for the passage of the derrick operating cables from the sheaves 42 and these cables are passed over and between sheaves 62 and thence up the boom to the usual sheaves carried by the upper end thereof. The sheaves 62 are arranged at the opposite side of the mast from that which opposes the removable plate 53, so that when the pin 58 is removed and the mast swung to horizontal position, these cables extend over the yoke to the head of the mast. The mast when in horizontal position lies over the carriage and may be

held by a suitable support, not herein shown

From the foregoing, it will be obvious that a derrick mast mounted in accordance with my invention may be readily shifted from horizontal to vertical position, will be firmly held in its vertical position and is so mounted that it may be rotated to place the associated boom in any desired position. To render more convenient the handling of the mast, means are provided, as indicated at 64, for securing the bull wheel against rotation with relation to the carriage. These means are at present shown as comprising bolts engaging the bull wheel flange and the carriage.

Means of the construction shown in Figure 5 is employed for the purpose of preventing the vertical displacement of the bull wheel with respect to its pivot pedestal 16. This means comprises an annular series of locking elements 65 which are arranged in a groove 67 formed in the flange 47 and a groove 69 formed in the boss 44. The opposing sides of the grooves 67 and 69 only are open, and the locking elements 65 contact with the upper and lower walls of the grooves so as to maintain the bull wheel on its pivot pedestal 16. The locking elements 65 are smaller horizontally or in width than the corresponding dimension or depth of the groove 67, and they are maintained in the grooves 69 by set screws 68 so as to maintain the connection between the bull wheel and its pivot pedestal 16. The set screws 68 are carried by the flange 47 and have their inner ends arranged in engagement with the outer sides of the locking elements 65.

It will also be obvious that this structure is capable of a certain range of change and modification without materially departing from the spirit of the invention and I accordingly do not limit myself to such specific structure except as hereinafter claimed.

I claim:—

In a derrick, a main carriage, a casting carried by one end of the carriage, a bull wheel rotatably mounted upon the casting and having an apertured hub, the casting having a bore aligning with the aperture of the hub of the bull wheel and being provided with sheaves for the passage of operating lines for a derrick, a mast having a casting at its lower end, said casting being pivoted to the bull wheel to permit movement of the mast from a horizontal position where it overlies the main carriage to a vertical operative position, said casting and mast having bores aligning with the aperture of the hub of the bull wheel and means for guiding lines passed through said bores to the exterior of the mast.

In testimony whereof I hereunto affix my signature.

EARL H. MORRIS.
